R. T. PARISEN.
THERMOSTATIC VALVE.
APPLICATION FILED MAR. 17, 1916.

Patented Sept. 3, 1918.

UNITED STATES PATENT OFFICE.

ROBERT T. PARISEN, OF PITTSBURGH, PENNSYLVANIA, ASSIGNOR TO LAWSON MANUFACTURING COMPANY, OF PITTSBURGH, PENNSYLVANIA, A CORPORATION OF PENNSYLVANIA.

THERMOSTATIC VALVE.

1,278,002.

Specification of Letters Patent. Patented Sept. 3, 1918.

Application filed March 17, 1916. Serial No. 84,852.

To all whom it may concern:

Be it known that I, ROBERT T. PARISEN, a citizen of the United States, and resident of Pittsburgh, in the county of Allegheny and State of Pennsylvania, have invented 5 certain new and useful Improvements in Thermostatic Valves, of which the following is a specification.

This invention relates to a thermostatic 10 valve of the general type illustrated by Letters Patent No. 1,075,934, October 14, 1913, and No. 1,102,070, June 30, 1914, wherein the action of the thermostat is transmitted to the valve through interposed 15 movement-compounding levers, and the primary object herein is to provide a simplified and efficient construction, particularly with respect to the means employed for adjusting the mechanism to predetermined temperatures. As in Patent No. 1,075,934, the compounding levers are mounted on a support 20 that is adjustable in the direction of movement of the thermostat, and with the mechanism of the present invention this adjustment is had by rotating the support within 25 the valve body and thereby, by means of its threaded connection, adjusting it in the direction of movement of the thermostat. And in the preferred construction the arrangement 30 is such that the adjustment of the support is accomplished by rotating a cap-like part at the exterior of the valve body, whereby the temperature to be maintained is determined by graduations on the body 35 with which a pointer on the rotatable cap cooperates.

In the accompanying drawings, Figure 1 is longitudinal sectional elevation of the improved valve mechanism, and Fig. 2 is a 40 similar view taken at right angles to Fig. 1. Fig. 3 is a cross section on line 3-3 of Fig. 2. Fig. 4 is a detailed view of the adjustable support for the movement multiplying levers.

Referring to the drawings, 2 designates 45 the body of the valve having at one side the gas inlet 3 and at its opposite side the outlet 4. Projecting into the body from inlet 3 is the tubular bridge or extension 5 which 50 carries the ported valve seat 6. Confined within bridge 5 is the disk valve 7 which is mounted on stem 8 movable through the seat, the valve being held normally seated by spring 9.

At one side of body 2 is the annular open-end extension 10, internally threaded as shown, and adjustably uniting therewith is the annular externally threaded collar 11' of the cap-like closure 11. This collar is formed with the body embracing flange 12 60 cut away at 12' and formed with pointer 13 for coöoperating with the temperature indications 14 on body extension 10.

The portion of body 2 opposite its open side is formed with the tubular extension 15, threaded at 15' to connect with the wall of the water heater or other container, not shown, and projecting from this tubular extension is the copper or other thermostatic tube 16 which incloses the thermostatic rod 70 element 17, formed preferably of porcelain or other neutral material. The outer end of the rod may bear against a plug 16' which closes tube 16, and the inner end of the rod extends into the tubular body extension 15. 75

Within body 2 is a support for the movement compounding mechanism which operatively connects rod 17 with valve stem 8. As here shown this support consists of a bifurcated base 18 having at one end the 80 angularly projecting arms 19 and at its opposite end the similar arms 20, the latter being prolonged in the single arm 21 which is entered between the jaw-like lugs 22 projecting from the inner side of cap 11. Secured 85 to and projecting from bifurcated base 18 is the tubular externally threaded stem 23 which when support 18 is rotated is adjustable in the threaded bore 24 of body extension 15. Pivotedly mounted between the support arms 19 and 20 are the coöoperating movement-compounding levers 25. An assemblage of three levers is here shown, one being in engagement with the valve stem 8 for moving the valve in opposition to spring 95 9, while another of the levers projects across and is engaged by the extremity of thermostatic rod 17.

In operation, it will be understood that movement of rod 17 resulting from the contraction of tube 16 transmits movement through levers 25 to the valve, the arrangement being such that very slight contraction of tube 16 results in a materially greater movement of the valve. For adjusting or 105 setting the mechanism, it is only necessary to rotate cap 11 to place pointer 13 at the temperature desired, such rotation of the cap

rotating support 18 and correspondingly adjusting the threaded connection between stem 23 and the valve.

The valve body may be provided with a 5 by-pass 26, controlled by valve 27 for passing sufficient gas through the body and around valve 7 to sustain a pilot-burner. Or if an external pilot-burner connection is desired, it may extend from the plugged 10 outlet 28.

I claim:

1. The combination of a valve body having a valve seat, a valve, a thermostatic device, a support rotatable within and having threaded connection with the body for adjusting the support in the direction of movement of the thermostat, a part rotatable at the exterior of the body and connected to the support for rotating the latter, and means carried by the support for operatively connecting the valve and the thermostatic device.

2. The combination of a valve body having a valve seat, a valve, a thermostatic device, a support rotatable in the body and having threaded connection therewith for adjusting the support in the direction of movement of the thermostat, coöperating movement compounding levers carried by 25 the support and operatively connecting the valve and thermostatic device, and means located at the exterior of the body for adjusting said support.

3. The combination of a valve body having a valve seat, a valve, a thermostatic device, a support rotatable within and having threaded connection with the body for adjusting the support in the direction of movement of the thermostat, the valve body 35 open at one side and a rotatable closure for said open side, an operative connection between the closure and the support for causing the latter to rotate with the closure, and means carried by the support for operatively connecting the valve and the thermostatic device.

4. The combination of a valve body having a valve seat, a valve, a thermostatic device including a valve actuating rod projecting into the body, a support rotatable within the body about an axis concentric with said rod and having a correspondingly concentric threaded connection with the body whereby rotation of the support adjusts the 50 same in the direction of movement of the thermostat, means carried by the support for connecting the valve and the thermostatic device, and a cap threaded to said body for adjusting said support.

5. The combination of a valve body having a valve seat, a valve, a thermostatic device, a support rotatable within the body

concentrically with the thermostat and the valve axis, the support having threaded connection with the body whereby when the 65 support is rotated it is moved longitudinally of the thermostat, coöperating movement-compounding levers carried by the support and operatively connecting the valve and the thermostat, and means located exteriorly 70 to said body for rotating said support.

6. The combination of a valve body having a valve seat, a valve, the body open at one side and a rotatable closure therefor adjustably connecting with the body, a support rotatable within the body and having threaded connection therewith whereby when the support is rotated it is moved longitudinally of the thermostatic device, an arm projecting from the support and engaged by the closure whereby the support and closure are caused to rotate in unison, and means carried by the support for operatively connecting the valve and the thermostat.

7. The combination of a valve body having a valve seat, a valve, the body formed with a tubular extension adapted to connect with the wall of a water container, a thermostatic tube projecting from said extension, a rod within and actuated by the tube with one end of the rod extending into the tubular body-extension, a support longitudinally arranged within the body and having a hollow supporting neck portion longitudinally adjustable in said body extension and embracing and adjustable longitudinally of said rod, means carried by the support for operatively connecting the valve and said rod and a cap threaded to said 100 body and having connection with said support for rotating the same.

8. In combination, a valve body having a port, a valve controlling said port, said body having a longitudinally threaded bore 105 at its inner end, a threaded rotary supporting neck screwed into said bore and adjustable longitudinally thereof and provided with a lever support arranged within the body, a series of movement-compounding 110 levers carried by said support and controlling said valve, a thermostat comprising a rod movable in said neck for actuating said lever, and means operative at the exterior of said body and having operative 115 connection with said support for rotating the same and said neck.

In testimony whereof I affix my signature in presence of two witnesses.

ROBERT T. PARISEN.
